UNITED STATES PATENT OFFICE.

THOMAS A. DOOLEY, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

METALLIC CAR END.

1,208,928.

Specification of Letters Patent. Patented Dec. 19, 1916.

Application filed November 6, 1914. Serial No. 870,584.

To all whom it may concern:

Be it known that I, THOMAS A. DOOLEY, a citizen of the United States, residing at the city of St. Louis, State of Missouri, have 5 invented a certain new and useful Improvement in Metallic Car Ends, of which the following is a full, clear, and exact description, such as will enable others skilled in the art to which it appertains to make 10 and use the same, reference being had to the accompanying drawings, forming part of this specification, in which—

Figure 1 is a front elevation of a metallic car end illustrating the preferred form of 15 my invention. Fig. 2 is a side elevation of the same. Fig. 3 is a detail of a cross section taken on line 3—3 of Fig. 1. Fig. 4 is a detail showing a vertical section taken on line 4—4 of Fig. 3. Fig. 5 is a detail 20 illustration of a cross section of a modified form. Fig. 6 is a detail showing a vertical section of said modification taken on line 6—6 of Fig. 5. Fig. 7 is a detail illustrating a cross section taken on line 7—7 of 25 Fig. 1.

My invention relates to metallic car ends which are intended for use on box cars, the same being designed as either a part of the original construction of the car, or as a 30 pair end which may be supplied to ordinary box cars in which the end has been broken.

The purpose of the invention is to provide a very strong and stable end construction which may be manufactured and 35 stalled very economically, and which may be easily repaired.

In the use of metallic car ends, and particularly those forms in which transverse corrugations are provided so as to stiffen 40 the end horizontally, it has been observed that the metal is likely to fail adjacent the corner posts or between the corner posts and the ends of the corrugations which terminate on or short of the corner posts. These 45 failures are due to the fact that a certain area of flat metal is left at the ends of the corrugations for attachment to the corner posts or for the formation of the inwardly turned flanges by which the sheet metal is 50 attached to the frame members of the car. Frequent failures are found to occur at the point of junction of the sections, to prevent which various expedients have been resorted to to reinforce the structure at the line of

junction, all of which increases the cost of 55 construction. It is my purpose, therefore, to provide a form of car end construction which is free from these various insufficiencies, and this I accomplish by the provision of corner posts of special form and 60 the use of sheet metal sections having corrugations which extend clear to the marginal extremities of the sheets and which are secured to the corner posts.

Referring now to Figs. 1, 2, 3, 4, and 7, 65 wherein the preferred form of my invention is illustrated, it will be understood that 1 represents the end sill of a car, 2 a side sill, and 4 the longitudinal side framing members. I supply the corner post 5, which is 70 in the form of a cast or pressed bar member, formed at its lower extremity with the flanges 6 which are adapted for attachment to the underframe members, and at its upper extremity with the bracket 7 or similar 75 portions which afford attachment for the side and roof framing members.

As will be seen in Fig. 3, the corner post is of general L-shape in cross section, having the front member 8 and the side member 9. 80 The front member 8 terminates in a sinuous flange 8^a, and the side member 9 is provided with an inwardly directed sinuous flange 9^a.

One or more sections of sheet metal 10 may be used. These sections are sinuously 85 corrugated across their entire width, the corrugations being regular and on the same center. The corrugations may be formed in this sheet either as a part of the original rolling process, or they may be pressed cold 90 into this conformation. This is a signal advantage over the manufacture of corrugated sections in which the corrugations terminate short of the edges of the sheet, as it does not require reheating of the metal, 95 and the metal is not stretched, and consequently weakened, as is frequently the case when the metal is hot pressed into special shapes. The contour of the flanges 8^a and 9^a is such as to conform to the outer and 100 inner sides respectively of the sections 10, there being a clearance between the confronting faces of said flanges sufficient to receive the thickness of the corrugated sections between them. In practice, it may be 105 desirable to make this clearance a trifle less than the thickness of the sheet metal in order to compensate for any inaccuracies in

the casting, and to insure a close and snug joint. When the sheet metal sections are placed in position, the flange 9^a laps behind the edge of the sheet metal, and the flange 8^a lies upon the outer side of the sheet metal, thus clamping the edge of the section. The sheet metal is fastened to the flange 8^a by rivets 11 which are seated in the tops of the outwardly convexing corrugations. This disposes the heads of the rivets on the inside of the car in the concave corrugations, and being thus inset, there is no danger of their coming in contact with the cargo, a very desirable arrangement especially in the carrying of explosives which might be discharged by concussion imparted to them by a rivet struck on the exterior of the car.

As will be seen from Figs. 3 and 4, the portion of the front member 8 intermediate the flange 8^a and side member 9, is slightly offset from the flange 8^a, thus providing a vertical channel 12 on the outside of the section. This channel provides a runway for any water which might work through the joint between the flange 8^a and the sheet metal. This water will flow downwardly and escape through a suitable opening at the bottom. This construction, therefore, protects the inner joint between the inner flange 9^a and the edge of the section against weather, and forms a practically impervious joint.

In Figs. 5 and 6 is illustrated a modified form in which a sinuous liner plate or angle member 14 is employed instead of the flange 9^a. In this form, the sinuous flange 8^a, section 10, and liner plate 14 are all secured together by the rivets, and the front member 40 is formed with a shoulder 15 against which the inner edge of the sheet metal abuts and upon which the edge of the liner plate lies, overlapping the edge of the sheet metal.

Where the different sections 10 are joined together, they are overlapped so that the marginal corrugations nest together and riveted through at the top of an outwardly convexing corrugation. When the end is in place, the side sheathing of the car is suitably secured to the side member 9, as illustrated in Figs. 2 and 5.

This construction is equally adaptable to a car end in which the corrugations are disposed vertically instead of transversely. In this case, the marginal members of bar material, instead of being corner posts will be formed as portions of the end sill and fascia, which will engage the corrugated top and bottom margins of the vertically disposed sections.

From the foregoing, it will be understood that this construction forms a very strong and very stable car end which will effectively resist the weaving movements of the car body, and which is free from weak

areas. The continuous corrugations, extending as they do from margin to margin of the sheet metal, and being secured to the specially formed marginal members, provide a specially rigid and thoroughly reinforced structure. 70

I am aware that my invention may be incorporated in various forms other than those herein shown and described. Consequently, it is not my intention that my invention be limited to these specific forms, but that it cover all other forms and other changes and modifications properly within its spirit and scope. 75

What I claim is:

1. A car end including a sheet metal section, and a corner post adapted to engage the marginal portion of the section along two lines and formed with a vertical channel intermediate said lines. 80

2. A car end including a sheet metal section, and a corner post adapted to engage the section at its margin and on a line inside the margin, said corner post being formed with a vertically disposed channel disposed 90 intermediate the said lines of contact. 85

3. A car end including a sheet metal section, and a corner post formed with a portion adapted to engage a margin of the section, a portion adapted to engage the section inside the margin, and a vertically disposed channel intermediate said portions. 95

4. A car end structure comprising angle bars forming corner posts, corrugated metallic sections extending intermediate the angle members and secured to flanges thereof, said flanges being corrugated to conform to the surface contour of the sections, and members conforming to the inner face of the sections and coöperating with said flanges to 100 retain the margins of the sections. 105

5. In a railway car structure, the combination of a corrugated metallic section forming a wall portion, and post members secured at their extremities to upper and lower car 110 framing parts and including retaining members overlapping opposite sides of the section and shaped to conform to the corrugated contour thereof.

6. A car end structure including a corrugated section forming an end wall portion, corner post members for supporting said section, said corner post members including transversely extending portions adapted to engage opposite faces of the section and 115 shaped to conform to the surface contour thereof. 120

7. In a car end structure, an end wall section, and a corner post for supporting the same, said corner post having a vertically 125 disposed channel traversed by the outer surface of the section.

8. In a car end structure, an end wall section, and a corner post member arranged to support the end wall section and having a 130

vertical drainage channel disposed in communication with the outer surface of the wall section.

9. A car end composed of sections of sheet metal which are sinuously corrugated across their entire width and conjoined at their meeting margins, and frame members co-operating with the said sections along their corrugated edges to form a closure, said frame members having portions engaging opposite sides of the sections and sinuously corrugated to conform to the contour of the sections.

10. A car end including a sheet metal section forming a wall portion, and a supporting member therefor, said supporting member having a sinuous portion engaging the exterior face of the section and secured thereto and a portion overlapping and abutting the inner face of the section, said portions being spaced apart to an extent less than the thickness of the sheet metal of the section.

11. In a car end structure, a framing member having sinuous flanges extending parallel and spaced apart, and a flange integral with and extending angularly relative to the sinuous flanges.

12. In a car end structure, a post including a side member and spaced apart sinuous flanges extending angularly therefrom.

13. In a car end structure, the combination of a sheet metal wall plate, and a post member adapted to support said wall plate, said post member having engaging portions 35 adapted to engage opposite sides of the wall plate, said engaging portions being spaced apart from each other in a direction transversely of the margin of the wall plate and being spaced apart in the direction of the 40 plate's thickness to an extent less than the thickness of the plate.

14. In a railway car structure, a wall section and a post for supporting the same, the post including a vertically extending channel portion traversed by the wall section and closed by the outer surface thereof.

15. In a railway car structure, a sheet metal section forming a wall portion, and an integral framing member to which the 5 said section is attached, said framing member having flange portions engaging opposite faces of the section, said flange portions being spaced apart to an extent less than the thickness of the section.

In testimony whereof I hereunto affix my signature in the presence of two witnesses, this 2nd day of November, 1914.

THOMAS A. DOOLEY.
